UNITED STATES PATENT OFFICE.

MURDOCK MACDONALD, OF CLEVELAND, OHIO.

HOLDER FOR TICKETS AND THE LIKE.

1,269,723.

Specification of Letters Patent. Patented June 18, 1918.

Application filed October 9, 1916. Serial No. 124,488.

To all whom it may concern:

Be it known that I, MURDOCK MACDONALD, a citizen of the United States, and a resident of Cleveland, county of Cuyahoga, and 5 State of Ohio, have invented a new and useful Improvement in Holders for Tickets and the like, of which the following is a specification, the principle of the invention being herein explained and the best mode in which 10 I have contemplated applying that principle, so as to distinguish it from other inventions.

The present invention, relating as indicated to ticket holders, has more particular 15 regard to a ticket holder of the type in which a pad of tickets are held in such position that they may be moved bodily into the casing a slight distance for the purpose of bringing the stubs into the upper portion or 20 roof of the casing, where these stubs are retained. Ticket holders of this general type are in quite common use on electric railways, for holding pads of tickets or of transfers.

One of the objects of the present invention 25 is to provide, in such a holder, means for indicating the date of issue of the ticket on that portion of the ticket which is normally outside of the casing, and which serves as the ticket proper. In city street railways it 30 is customary to provide the conductors with pads of transfers, and in order to save as much as possible of the punching on this transfer, it is usual to stamp or print the date on each pad of transfers, and to issue 35 new pads every day. This procedure entails a considerable waste, since the unused transfers are of no further value, and it is estimated that in some very large cities, where this system is used, the waste from unused 40 transfers is several thousand dollars annually. If means can be provided to date each transfer (or ticket as the case may be) only when actually issued, a very large saving can be effected. At the same time such 45 means cannot be at all complicated and this has in the past been an insurmountable difficulty. My invention provides a very simple and effective means for so dating the tickets or transfers. To the accomplishment 50 of the foregoing and related ends, said invention, then, consists of the means herein-after fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Figure 1 is a transverse, vertical section through a ticket holder of the type described, in which is incorporated my improved means for printing on the tickets; Fig. 2 is a vertical section on the line 2—2, 65 Fig. 1 showing one type of construction; Fig. 3 is a similar view showing another and a preferred construction; Fig. 4 is an end view of the ticket holder shown in Figs. 1, 2 and 3; Fig. 5 is a view of the transfer such 70 as is used in this type of holders, and Figs. 6 and 7 are vertical sections on the lines 6—6 and 7—7, in Figs. 2 and 3, respectively.

The general construction of the ticket holder of this type, is best seen from Fig. 1 75 in which there is shown a casing 1 provided with an arched top or roof 2 into which the stubs 3 of a pad of tickets 4 are adapted to spring when the pad is moved bodily inward. The casing 2 is provided with an 80 open side, which is partly covered by means of a plate 5 hinged to the casing about an axis 6, and which is normally pressed outwardly by means of a coiled spring 7, one portion of which is formed into a loop 8 85 adapted to hold the ticket pad 4 upon the side 5 and in engagement with pins 9 mounted thereon, and adapted to be inserted in apertures formed in the pad. The pad extends externally of the casing between the 90 bottom of the right hand side and the edge of the side 5. This side 5 is normally maintained in about the position shown in Fig. 1 by means of locking rods or bars 10 which are adapted to be moved laterally to engage 95 behind flanges formed on the bottom edges of the two ends of the casing. This side 5 is then locked against movement in a clockwise direction, and is normally maintained against movement in the opposite direction 100 by means of the spring 8 but may be swung inward in order to release the stubs of the tickets. This type of holder is one that has recently come into quite general use and is here shown for that reason but it will be 105 evident that other types may equally well be

used in conjunction with the printing mechanism to be hereinafter described.

One form of ticket used is shown in Fig. 5, and it will be understood that these tickets are so held that a column 12, between the columns 13 and 14 indicating the hours of the day, lies adjacent to the edge of the righthand side of the casing and directly beneath marking fingers 15, slidably mounted upon a guide 16, affixed to the outside of the casing. The stub portion of the ticket is thus that part to the left of this blank column shown in Fig. 5, while the ticket or transfer proper is that part to the right of this column. The stubs 17 at the bottom of the transfer are usually printed with the names of the lines or streets for which the transfer is issued, while the hour of the day is indicated by a notch formed in the edge 20 of the upper columns of the ticket by means of the marking fingers 15. While I have here illustrated a transfer ticket on which a date is to be printed it will be understood such showing is not intended to restrict the use of the invention to this specific ticket. Thus, it might equally well be applied to the printing of different data, whether on a transfer, ticket or other coupon. Accordingly, the use of the expression dating or 30 printing the date in the following description includes the indicating of data of any desired character on a ticket, coupon or the like.

The means for indicating the date of issue 35 of the transfer consist of type-bearing sleeves removably mounted upon a shaft 21 which is in turn removably mounted on the inner wall of the front side of the casing. On the shaft 21 there is mounted a stop 20 provided with a notch 40 and the first of the sleeves 30 is mounted on the shaft and engaged against this stop. A lug 31 on the end of the sleeve fits into the notch and prevents rotation of the sleeve except with the shaft. If necessary other sleeves 32 and 33 45 may be used, each sleeve bearing suitable type and the sleeves being non-rotatably engaged by grooves 34 and lugs 35. Thus in a device adapted to print a date, there will 50 preferably be three sleeves 30, 32 and 33 bearing respectively, the year, the day of the month and the month in abbreviated form. The type on the sleeves is normally 55 in contact with an inking roller 22 disposed parallel with the shaft 21. The shaft 21 is normally maintained in the position shown in Figs. 2 and 3 by some resilient means, either in the form of a flat spring 23 (see Figs. 2 and 6) or in the form of a spiral 60 spring 24 (see Figs. 3 and 7). Preferably, however, a spiral spring 24 is used, being connected at one end 25 to the side of the casing, and at its other end to the shaft 21. Mounted on this shaft 21 are two small 65 gears or sprockets 26 which are adapted to

engage against the surface of the ticket pad, when the latter is moved inward by movement of the side 5, and to be thus rotated sufficiently to bring the type against the space to the right of the blank column on the ticket. 70

The sprockets 26 will always be maintained in an operative position with respect to the ticket pad, since this pad, when moved inward, is brought against these rollers and is moved across the same, thus rotating the rollers and the type. 75

The shaft 21 and the inking roller 22 are adapted to be removed from the casing through an opening 27 formed in the end 80 of the same, which is normally covered by means of a cap 28. It will be necessary to remove two of the sleeves every day, in order to change the day of the month, while the inking roller will only need to be removed and renewed about once a year. 85

The present device comprises a very simple and effective means for printing the date on transfers or tickets, this printing being automatic upon the movement of the pad of tickets into the casing, which has to be done after the tearing off of every ticket, in order to push the stub into the roof of the casing, and it being impossible for the conductor to tamper with this means of dating 95 the tickets. Furthermore, the present invention can be readily incorporated in not only the type of holder here illustrated, but also in other types, since it is necessary only that there be slight relative movement between the type bearing members and the ticket, which can readily be secured either as here shown or by a movement of the printing mechanism across the pad of tickets. 100

Other modes of applying the principle of my invention may be employed instead of the one explained, change being made as regards the mechanism herein disclosed, provided the means stated by any of the 110 following claims or the equivalent of such stated means be employed.

I therefore particularly point out and distinctly claim as my invention:—

1. In a ticket holder of the character described, the combination of a casing, means adapted to hold a ticket pad therein with a portion thereof extending from said casing, actuating means adapted to move said pad into said casing, and printing means actuated upon such movement of said pad and adapted thereupon to print the date on the portion of said ticket normally lying outside of said casing. 115

2. In a ticket holder of the character described, the combination of a casing, means adapted to hold a ticket pad therein with a portion thereof extending from said casing, actuating means adapted to move said pad into said casing, printing means mount- 120 125 130

ed within said casing, said means being actuated upon such movement of said pad and being adapted to print the date on the portion of said ticket normally lying outside of said casing.

5 3. In a ticket holder of the character described, the combination of a casing, means adapted to hold a ticket pad therein with a portion thereof extending from said casing, actuating means adapted to move said pad into said casing, a date printing roller mounted within said casing, said roller being actuated upon such movement of said pad and being adapted to print the date 10 on the portion of said ticket brought into 15 said casing by such movement.

4. In a ticket holder of the character described, the combination of a casing, means adapted to hold a ticket pad therein with a portion thereof extending from said casing, actuating means adapted to move said pad into said casing, a date printing roller mounted within said casing, a sprocket attached to said roller and adapted to be engaged by said pad upon movement of the same, said roller being thereby rotated to print the date on the portion of said ticket brought into said casing by such movement.

5. In a ticket holder of the character described, the combination of a casing, means adapted to hold a ticket pad therein with a portion thereof extending from said casing, actuating means adapted to move said pad into said casing, a shaft mounted within 35 said casing, a sprocket mounted thereon in position to be engaged and rotated upon such movement of said pad, and a type-bearing member removably mounted in said casing and actuated by rotation of said shaft to 40 contact and print the portion of the pad normally lying outside of said casing.

6. In a ticket holder of the character described, the combination of a casing, means adapted to hold a ticket pad therein with a portion thereof extending from said casing, actuating means adapted to move said pad into said casing, a shaft mounted within said casing, a sprocket mounted thereon in position to be engaged and rotated upon 50 such movement of said pad, and a type-bearing sleeve non-rotatably but removably mounted on said shaft, said sleeve being actuated by rotation of said shaft to contact and print the portion of the pad normally 55 lying outside of said casing.

7. In a ticket holder of the character described, the combination of a casing, means adapted to hold a ticket pad therein with a portion thereof extending from said casing, 60 actuating means adapted to move said pad into said casing, a shaft mounted within said casing, a sprocket mounted thereon in position to be engaged and rotated upon such movement of said pad, a type-bearing sleeve non-rotatably but removably mount-

ed on said shaft, said sleeve being actuated by rotation of said shaft to contact and print the portion of the pad normally lying outside of said casing, and inking means mounted in said casing and adapted to supply ink to such type on said sleeve.

8. In a ticket holder of the character described, the combination of a casing, means adapted to hold a ticket pad therein with a portion thereof extending from said casing, actuating means adapted to move said pad into said casing, a shaft mounted within said casing, a sprocket mounted thereon in position to be engaged and rotated upon such movement of said pad, a type-bearing sleeve non-rotatably but removably mounted on said shaft, said sleeve being actuated by rotation of said shaft to contact and print the portion of the pad normally lying outside of said casing, and an inking roller 75 80 85 rotatably mounted in said casing parallel to said shaft, said roller being normally in contact with the type on said sleeve.

9. In a ticket holder of the character described, the combination of a casing, means adapted to hold a ticket pad therein with a portion thereof extending from said casing, actuating means adapted to move said pad into said casing, a shaft mounted within said casing, a sprocket mounted thereon in 90 position to be engaged and rotated upon such movement of said pad, a type-bearing sleeve non-rotatably but removably mounted on said shaft, said sleeve being actuated by rotation of said shaft to contact and print the portion of the pad normally lying outside of said casing, and an inking roller rotatably and removably mounted in said casing parallel to said shaft, said roller being normally in contact with the type on 95 100 105 said sleeve.

10. The combination of a casing adapted to hold a pad of tickets, a printing roller disposed adjacent to the uppermost of such pad of tickets in said casing, means adapted to move the uppermost of such pad of tickets transversely of said roller, and a member mounted on said roller and adapted to engage and be rotated by such pad, thereby rotating said roller.

11. The combination of a casing adapted to hold a pad of tickets, a printing roller disposed adjacent to the uppermost of such pad of tickets in said casing, means adapted to move the uppermost of such pad of tickets transversely of said roller, and a sprocket mounted on said roller and adapted to engage and be rotated by such pad, thereby rotating said roller.

12. The combination of a casing adapted to hold a pad of tickets, one side of said casing supporting said tickets and being movable with respect to said casing, and printing means mounted within said casing above such pad of tickets, said means be- 125 130

ing operable to print the uppermost ticket upon inward movement of said movable side of said casing.

13. The combination of a casing adapted to hold a pad of tickets, a rotatable printing roller mounted within said casing above the normal position of such pad of tickets, and a hinged side on said casing adapted

to support such pad of tickets, said side being adapted, upon movement, to bring such pad of tickets in contact with said printing roller and to move such pad transversely of said roller.

Signed by me, this 6th day of October, 1916.

MURDOCK MACDONALD.
